 Netherlands

Application June 22, 1937, Serial No. 149,582
 In the Netherlands June 22, 1936

2 Claims. (Cl. 250—174)

The invention relates to electron discharge tubes which comprise a cathode, one or more control elements, an anode and a so-called secondary emission electrode which is an electrode whose surface may readily emit secondary electrons, and more particularly to the form of construction of such a discharge tube.

According to the invention, the anode is not located in the path of the primary electrons, so that the latter cannot reach it. When all of the secondary electrons are drawn away by the anode, a variation of the anode voltage brings about only a slight current variation, so that a high internal resistance is obtained.

It is advantageous to utilize a form of construction wherein the control and screen element are in the form of plates or solid elements which surround part of a preferably indirectly heated cathode and act as a kind of electron gun, while the secondary emission electrode is mounted opposite other parts of the cathode in position to be struck by the beams from the electron gun. The anode may be arranged outside the path of the primary electrons in such manner that it can be struck only by the electrons emanating from the secondary emission electrode.

The invention will be understood more easily by reference to the accompanying drawing which represents diagrammatically in cross section one form of construction with the electrodes of a discharge tube arranged according to the invention.

Referring to the drawing, 1 denotes a tubular indirectly heated cathode inside of which is an insulated heating element; 2 and 3 denote a control element and a screen or accelerating electrode respectively, each of the duplex type with two solid parts, such as metal sheets, mounted on opposite sides of the cathode to form a kind of electron gun which produces a modulated beam of primary electrons. Opposite the intermediate sides of the cathode, which are between the two sheets or parts of the control element 2, is located the electrode 4, with the surface exposed to the modulated beams coated with a secondary electron emission material which readily emits secondary electrons. Outside the path of the primary discharge or electron beam, which is lengthwise of and between the two sheets of the control element, and beyond the end of the accelerating electrode 3, is an anode 5. As indicated in the drawing by broken line arrows, the primary electrons may flow from the cathode to the secondary emission electrode 4 in

a beam which is influenced and modulated by the electrode 2 and accelerated by the electrode 3. Secondary electrons emitted by the secondary emission electrode 4, due to bombardment by the primary modulated beams, may flow to the anode 5 along the lines indicated by dotted arrows. Variations in the primary stream cause in the flow of secondary electrons to the anode 5 corresponding and magnified variations, which are substantially independent of variations in voltage on the anode.

We claim:

1. An electron discharge tube comprising an indirectly heated cathode, a control element comprising a pair of metal sheets mounted on opposite sides of said cathode to form a passage for the discharge from said cathode, an accelerating electrode comprising a pair of metal sheets on opposite sides of and parallel to said control element, a secondary electron emission electrode in alignment with the passage between the sheets of said control element, and an anode between said secondary electron emission electrode and the end of said accelerating electrode and outside the electron path extending from the cathode through the passage in the control element to said secondary emission electrode.

2. An electron discharge tube comprising a rectilinear cathode, beam forming means adjacent said cathode consisting of an equipotential accelerating electrode comprising a pair of conductors mounted on opposite sides of and parallel to said cathode to form the electron discharge from said cathode into an electron beam, said conductors being wider than the diameter of said cathode and spaced to provide for said electron beam an unobstructed passage between said conductors of a width as great as the spacing between said conductors, a unipotential control electrode adjacent said cathode and between said accelerating electrode and said cathode, a secondary electron emitter mounted beyond the ends of said accelerating electrode conductors and opposite the passage between said conductors and extending across and perpendicular to the path of said electron beam, and an output anode mounted between said emitter and said conductors out of alignment with said passage and outside the path of said electron beam to said emitter.
